6 Claims. (Cl. 18—19)

This invention relates generally to dolls' eyes and, more particularly, to a method of, and apparatus for curling the lashes of a doll's eye.

Curved lash dolls' eyes are desirable to more realistically simulate the human eye and lash and increase the play value and fascination of dolls having such eyes as components thereof. Dolls' eyes having curled lashes have had very limited application heretofore, based essentially on the fact that no commercially feasible method or apparatus was available to produce curled lashes. Curled lashes have been produced by laborious and expensive hand methods in which curvature control was difficult and curvature reproducibility was something to be desired. Furthermore, the curvature imparted to the lashes was lacking in permanence, with curvature changes being effected at elevated temperature and/or humidity conditions.

The primary aim and object of the present invention is the provision of a method of, and apparatus for, curling the lashes of a doll's eye in which the aforesaid deficiencies of the heretofore made curled lashes have been obviated. More particularly, pursuant to the method and apparatus of the present invention, high quality, aesthetically attractive curled lashes for dolls' eyes may be produced on a commercially feasible scale, with the resultant curled lashes having controlled curvature which is mass-reproducible and permanent.

Another object of the present invention is the provision of a method of curling the lashes of a doll's eye which is susceptible to low-cost mass production techniques and in which the curvature of the resultant lash is permanent.

Another object of the present invention is the provision of apparatus for curling the lashes of a doll's eye which carries out the aforesaid method on a mass production scale to produce and reproduce curled lashes of permanent predetermined curvature, said apparatus being of simple design and construction, reliable in operation, and eminently suitable for carrying out the method of the present invention.

Another object and feature of the present invention is the provision of controlled uniformly spaced or distributed and fanned out lashes, the spacing and fanning out being adjustable as desired or required in a simple and facile manner.

To the accomplishment of the above and such other objects as may hereinafter appear, the present invention relates to a method of, and apparatus for, curling the lashes of a doll's eye as defined in the appended claims, and as described in this specification, taken together with the accompanying drawings in which:

FIG. 1 is a top perspective schematic view of a dial machine in accordance with the present invention and embodying a series of units for curling the lashes of a doll's eye;

FIG. 2 is a top perspective view of a unit for curling the lashes of a doll's eye and of a doll's eye preparatory to the curling of the lashes thereof, the slide of the unit being shown in an opened or retracted position for the loading of the doll's eye on the post;

FIG. 2a is a view of the doll's eye of FIG. 2 showing the lashes after the curling operation and prior to trimming;

2

FIG. 2b is a view of the doll's eye with the lashes trimmed;

FIG. 3 is a side view of the curling apparatus or unit with the dial plate shown in section, the slide and clamping device being shown open;

FIG. 4 is a view similar to FIG. 3, with the slide and clamping device shown closed;

FIG. 5 is a longitudinal sectional view through the curling apparatus with the slide and clamping device shown closed, and with the lashes formed and clamped against the forming member;

FIG. 6 is a view similar to FIG. 5, showing the slide advanced from the FIG. 5 position to space the formed clamped lashes from the forming member;

FIG. 7 is a sectional view, on an enlarged scale, taken on the line 7—7 of FIG. 4;

FIG. 8 is a sectional view, on an enlarged scale, taken on the line 8—8 of FIG. 4;

FIG. 9 is a sectional view, on an enlarged scale, taken on the line 9—9 of FIG. 4, with a doll's eye positioned on the post;

FIG. 10 is an enlarged fragmentary side view showing the cam and follower assembly for operating the clamping device;

FIG. 11 is a sectional view taken on the line 11—11 of FIG. 10;

FIG. 12 is a plan view of the lash spacing and fanning device shown disassembled from the curling apparatus; and

FIG. 13 is a fragmentary sectional view, on an enlarged scale, taken on the line 13—13 of FIG. 12.

Referring to the drawings, and more particularly to FIGS. 2, 2a and 2b thereof, there is shown a doll's eye 10 having lashes 22 in an intermediate stage of manufacture which are adapted to be processed to form finished lashes 22' of doll eye 10 pursuant to the method and apparatus of the present invention. The doll's eye 10 may be of any suitable design and construction, and in the illustrated embodiment said eye comprises a generally hemispherical eye member or shell 12 having a lens L which consists of a pupil 14 surrounded by an iris 16. The lens may be of any desired construction and may be integrally formed with the eye member, as shown for example in Patent No. 2,828,581, issued on April 1, 1958, for Movable Doll Eye in the name of R. I. Prupis and assigned to the assignee herein, or, if desired, said lens may be separately formed and suitably integrated with the eye shell or member. The eye member of the illustrated embodiment includes a pair of diametrically opposed projecting flanges 18 which are characteristic of the particular eye shown, said eye being of the type in which a pair of such eyes are adapted for mounting on a cross rod so as to move in unison between sleeping and open positions in a manner well known in the art. The eye member or shell 12 may be of any other desired construction or configuration, and for example may be of the individually movable type which is used for soft plastic doll heads now in vogue, as shown and described in the aforementioned Prupis patent. The doll's eye itself apart from the lashes forms no part of the present invention and thus it is considered unnecessary to further describe the eye apart from the lashes.

The hemispherical eye shell is slit or slotted on an arcuate line 20 over the iris 16, and the lash 22 is inserted and cemented in place in any desired manner. The lash is flexible and is made up of a multiplicity of generally parallel projecting strands which are arcuately arranged over the lens L along the line 20. In the instant embodiment the lashes are formed of Nylon 66 polymer monofilament material, which is eminently suitable for the practice of the instant invention in that said material is en-

dowed with the capacity to shrink on the application of heat thereto and is thermally settable in a shrunk condition, as will be described in detail below. It will also be apparent that other stranded material in slit or filamentary form having the requisite characteristics aforesaid may be used. The lash 22 projects outwardly of the eye shell over the lens in visor-like fashion. The doll's eye 10' (FIG. 2b) is provided with a finished lash 22' which has been curled and trimmed, the lash 22 being transformed into lash 22b (FIG. 2a) by the curling operation to be described in detail hereinafter. A trimming operation is performed subsequently to trim the lashes to the desired length and shape along an arcuate line to define the lash ends 26 of lash 22'.

Briefly, the method of curling the lashes 22 comprises the steps of forming the lashes over a forming member 52 to impart a predetermined curvature thereto and clamping the thus formed lashes in the position as shown in FIG. 5. The formed clamped lashes 22a and the forming member are then relatively separated, as shown in FIG. 6, to permit the formed lashes to shrink to the broken line position 22b in a tensionless condition, while applying a heat source H to the formed lashes 22a in the FIG. 6 disposition thereof, thereby shrinking the same as indicated at 22b and imparting the desired curvature thereto. A cooling source C is next applied to the thus shrunk curled lashes in order to set the same at the desired curvature. In this manner a permanent set of the desired curvature is achieved which will withstand excessive temperature and humidity conditions considerably beyond the range of conditions to which the doll's eye will be subjected in use. It is emphasized that the nylon filamentary material of the exemplified embodiment has the capacity to shrink on the application of heat thereto and is thermally settable in a shrunk condition, and that these properties of the material have been determined to give the desired permanently set curvature. The aforesaid method, which will be referred to in greater detail below, may be carried out on the dial machine M (FIG. 1) having a series of curling units 30, which will now be described.

A series of curling units or apparatus 30 is mounted in predetermined spaced relation along the periphery of the dial plate or table 32, which is sequentially indexed to a series of stations where the operations to be described are performed. Associated with each unit 30 is an actuating member in the form of a cam follower 34 which rides in a peripherally extending cam groove 36 of a stationary cam plate 38 suitably mounted at the underside of the dial table 32. It will be understood that as the dial table rotates the cam follower 34 rides in cam groove 36 to impart the requisite reciprocatory motion to the unit 30.

The unit 30 (FIGS. 3-6) comprises a reciprocating slide 40 which is guided for such movement on the dial plate by the laterally spaced longitudinal rails 42 secured to the dial plate by screws 44. The cam follower or roller 34 (FIGS. 5 and 7) is mounted on a shaft 48 which is threadedly engaged to the slide at 46, the shaft 48 extending through the slot 50 of the dial plate with clearance. The slide 40 carries a forming member 52 having an arcuate wall 53 (FIG. 8) extending from base wall 55, said member being formed of a preferably heat insulating material such as Micarta or the like. The member 52 has a forming face 54 (FIG. 5) which is curved to conform to the arcuate extent of the lash 22, and has a rounded forward edge over which the lashes are curled. Thus the forming face 54 and lash 22 are of complementary arcuate configuration, and the forming face is curved with respect to a transverse axis, as best shown in FIGS. 5 and 6, for imparting a corresponding curvature or curl to the lash 22 at the lash forming phase of the cycle of operation.

Secured to the forming member 52 at the underside thereof is a device 55 (FIGS. 12 and 13) for spacing and

fanning out the lashes during the forming thereof, said device being constituted by a plate 56 having a series of needles 58 secured thereto. The plate 56 is provided with a pair of elongated slots 60 and a threaded mounting aperture 62 disposed therebetween. The forward part 64 of the plate is in the form of a conical segment, and includes a multiplicity of laterally adjacent longitudinal V grooves 66, each of which has a needle 58 secured therein, as by soldering or the like. The needles 58 are thus uniformly spaced and arranged to conform to a generally conical surface for spacing and fanning out the lashes, as will be apparent from the description which follows.

The plate 56 engages in the slot 68 provided therefor in the underside of the forming member 52, and is secured in position by the clamping screw 70 which extends through the elongated opening 72 of the forming member and is threadedly engaged in the mounting aperture 62. The plate 56 is longitudinally adjustable with respect to the forming member 52 by means of the clamping screw 70, this adjustment controlling the degree of fanning out of the lashes. More particularly, to increase the degree of fanning out the plate 56 is shifted forwardly of the member 52 to provide a greater stroke or projection of the needles through the lash in the forming operation, the plate being shifted reversely or rearwardly to decrease the degree of fanning out of the lashes. The needles are arranged in conical fashion, so that the greater the lash penetration in the forming operation, the greater the fanning out achieved.

The assembly constituted by the forming member 52 and device 55 is positioned on the face 74 of the slide, and is maintained in assembled relation therewith by means of screws 76 which extend through the registered elongated openings 78 and 60 of the forming member 52 and device 55, respectively. The elongated openings 78 open at the top to longitudinal recesses 79 extending below the top surface 53 of the forming member. The assembly constituted by the forming member 52 and device 55 are relatively movable with respect to the slide, the latter having an upstanding end flange 80 which is apertured, as indicated at 82, for the extension therethrough of a stop screw 84 which is threadedly engaged in aperture 86 of the forming member 52. The forming member is biased away from the flange 80 by means of the compression spring 88 which surrounds the screw 84, the spring extending between said flange and the forming member. The screw 84 has threadedly engaged thereon an adjusting nut 90, which is locked in position by a lock nut 92. The adjusted position of nut 90 determines the maximum advanced position of the forming member with respect to flange 80 and the slide 40. Thus the forming member 52 and the needle plate attached thereto are movable in unison with the slide, but are yieldable with respect to the slide under conditions to be described, through the interposition of spring 88. It will be understood that the screws 76 secured to the slide are mounted with clearance with respect to the forming member and needle plate to provide for such relative movement.

Centrally positioned at the forward part of the unit is a post 94 for releasably holding the doll's eye 10 in position during the lash curling operation. The post 94 is formed complementary to the eye shell 12 to releasably retain the same in prescribed oriented position, and accordingly is provided with a configuration which mates with the inside configuration of the eye shell. The post includes a peripheral shoulder 96 for the seating thereagainst of the peripheral edge 24 of the eye shell, and further includes diametrically opposed cutouts 98 to receive the flanges 18 of the eye shell. The engagement of the flanges 18 in cutouts 98 properly locates the instant eye shell for the lash curling operation. It will be understood that post 94 will be formed complementary to whatever eye member is to be seated thereon, the instant post design being complementary to the eye shell

12 of the exemplified embodiment. As shown in FIGS. 5 and 6, the post 94 is provided with a cavity 100 to receive the lens L with clearance. The post 94 is detachably mounted on the member 102 by means of bolt 104. The post 94 includes a downwardly projecting shank 126 which interfits in the slot 128 of the member 102 to locate said post. The transverse bar 103 (FIG. 9) of member 102 is suitably slotted or cut away, as indicated at 130, to provide the requisite clearance for the flanges 18 of the eye shell seated on the post. The member 102 is generally T-shaped and comprises the said transverse bar 103 (FIG. 9) and slide bar 105, the latter being mounted in the slot 101 (FIGS. 6 and 8) provided therefor at the underside of the dial plate 32. The member 102 is supported in position by the pin member 106 (FIGS. 5 and 6) having a shoulder portion 108 which rides on the rails 109 of the slot 110 of the dial plate 32, the threaded end 112 of pin member 106 being threadedly engaged in the opening 114 of bar 105. The member 106 includes an upstanding stud 116 which is disposed for engagement by a push pin 118, as shown in FIG. 6, to actuate member 102. The pin 118 is mounted in a longitudinal bore 120 of the slide 40, and its position is adjustably determined by the adjusting screw 122 which is threadedly engaged in the aperture 124 at one end of the slide. It will be understood that on predetermined advance movement of the slide towards the post the pin 118 will engage the stud 116 to push the member 102 to the right, viewing FIGS. 5 and 6. The bar 105 carries a pin 107 which is connected to the pin 107' by the spring 111, the pin 107' being fixed to the dial plate as indicated at 113 (FIG. 5). The pin 107' extends through an elongated slot 115, and bar 105 is biased into engagement with said pin by pull spring 111. The member 102 is thus relatively movable with respect to pin 107' on the engagement of pin 118 and stud 116.

The curling apparatus includes a clamping device which is arranged to open and close in response to slide movement, said clamping device comprising a pair of complementary interengageable clamping rings 132 and 134, the latter clamping ring being fixedly secured at its opposite ends to the slide by screws 136 (FIG. 9). The clamping rings are of a configuration complementary to the configuration of the forming face. The clamping ring 134 is fixed in position with respect to the slide, and interfits over the forming face 54 back of the leading edge thereof and adjacent to the peripheral shoulder 138 of said forming member, as shown in FIG. 5. The first clamping ring 134 is of rectangular cross section and is positioned to help clamp the free end portions of the lashes formed over face 54. The movable clamping ring 132 is interengageable with the clamping ring 134 for clamping the free end portions of the formed lash therebetween, and said clamping ring 132, which is also of rectangular cross section, is pivotally mounted to the member 102 along a pivotal axis extending longitudinally of bar 103, that is, transversely of the longitudinal axis of the curling unit. The member 102 thus carries the post 94 and clamping ring 132, that the clamping ring 132 and said post are movable in unison by the slide on the engagement of pin 118 and stud 116, after a predetermined travel of the slide towards the post. The opposite ends of the clamping ring 132 are pinned to stub shafts 140 and 140' (FIG. 9), as indicated at pins 142, said stub shafts being journaled for rotation in suitable bearings provided in bar 103. The stub shaft 140' has a crank arm 144 (FIG. 11) pinned thereto, as indicated at 146, which carries a screw 150 having a roller 148 rotatably mounted thereon. The roller 148 acts as a cam follower which is under the control of the cam plate 152 affixed to the slide.

The slide is provided with an upstanding side wall 154 (FIGS. 8 and 9) and the cam plate 152 is mounted laterally outboard of said side wall through the intermedia-

5 being mounted to the side wall 154 by screws 158 which extend through the apertures 160 (FIG. 2) and spacers 156, and are threadedly engaged in said side wall. The apertures 160 of the cam plate 152 are elongated in order to provide a range of adjustment for the cam plate relative to the slide. The cam plate 152 is provided with a cam slot 162 (FIG. 10) comprising inclined cam surfaces 164, straight cam surfaces 166, inclined cam surfaces 168, and straight cam surfaces 170, said cam surfaces coacting with the cam follower 148 on screw 150 to impart the requisite pivotal movement to the crank arm 144 and its clamping ring 132. With the slide in the fully retracted position, as shown in FIGS. 2 and 3, the follower 148 will be disposed at the extreme end of the cam slot 162 defined by cam surfaces 164, and the clamping ring 132 will be in the fully open position. As the slide and forming member advance towards the post the cam follower 148 rides up the lower cam surface 164 to thereby pivot the clamping ring 132 into engagement with the underside of the lashes 22, preliminary to the curling thereof. When the follower 148 reaches the end of cam surface 164 the clamping ring 132 will be disposed forwardly of the clamping ring 134 and out of clamping relation therewith. On further advance of the slide, with the follower 25 148 riding along lower horizontal cam surface 166, a dwell will take place in the pivotal movement of the clamping ring 132, during which the needles 58 will be advanced through the lashes or filaments to uniformly space and fan out the same, said needles extending through the narrow gap defined between the external surface of the eye shell and the underside of the forming face 54. On this phase of slide movement the lash will be preliminarily formed around the forming face by the engagement of the lashes with the clamping ring 132. On further advance of the 30 slide the follower 148 will ride up the inclined surface 168 to finish forming the lashes around the forming face, and to clamp the formed lashes in position, as shown in FIG. 5, the clamping action being completed at the end of sloping cam surface 168. At the terminal end of the advance 35 movement of the slide, the follower 148 will cooperate with the horizontal cam surfaces 170 of the cam slot.

40 On final advance of the slide the pin 118 engages the stud 116, and the assembly carried by the member 102 will be advanced to the position shown in FIG. 6, in which the engaged clamping rings and post will be advanced forwardly of the forming face so as to space the formed clamped lashes 22a from said forming face for permitting the formed lashes to shrink in a tensionless condition on the thermal treatment to be described.

45 50 Extending transversely at the rear of the forming member 52 in slot 172 thereof is a stop member 174 (FIGS. 3, 4, 7 and 8) which is disposed to engage a companion stop screw 176, which is fixedly disposed relative to the dial plate, to limit the advance movement of the forming member. The slide 40 includes a side wall 41 having a shoulder 43 which is spaced from the stop member 174 to provide clearance therebetween at the maximum advanced position of the forming member. Thus the forming member and slide coat as a unitary assembly, except when the forming member is arrested on the engagement of the stop member 174 with the stop screw 176 which takes place on the separation of the formed clamped lashes 22a from the forming face 54. The apparatus is timed so that the stud and pin 116 and 118, respectively, engage substantially simultaneously with the engagement of the stop member 174 and stop screw 176.

55 60 65 70 75 One rail 42 (FIGS. 4 and 8) is provided with an upstanding block 178 and screw 176 is threadedly engaged therethrough and is releasably retained in adjusted position by lock nut 180. It will be understood that on predetermined advance movement of the slide towards the post the stop member 174 will engage the stop screw 176 to arrest the movement of the forming member and the device 55 secured thereto, the further and terminal advance movement of the slide providing for the aforesaid

separation of the formed and clamped lash 22a from the forming face 54.

In practise, the post 94 is loaded with a doll's eye 10 at a loading station LS (FIG. 1) of the dial plate, at which station the clamping ring 132 is fully opened, and the slide fully retracted, as shown in FIGS. 2 and 3. As the dial plate rotates, the cam follower 34 coacts with its companion cam groove 36 to provide the requisite reciprocation to the slide 40. As the slide is advanced towards the post the clamping ring 132 will be pivoted towards and into engagement with the lashes 22 and the needles 58 will be projected through the lashes for spacing and fanning out the same, the pivotal movement of the clamping ring 132 being under the control of the slide through the cooperation of the cam follower 148 and the cam slot 162, as described above. The slide will continue its advance movement, and the clamping ring 132 will form the spaced and fanned out lashes over the forming face 54, as shown in FIG. 5, and the thus formed lash will be clamped in position over the forming face between the mating clamping rings 132 and 134. At this phase of the lash curling operation the advancing movement of the forming member 52 will be arrested through the engagement of member 174 with stop screw 176, and the continued advance of the slide will advance the eye shell 12 and clamping rings 132 and 134 with the lash clamped therebetween, away from the forming face 54 in order to space the then formed and clamped lash 22a from said forming face, as shown in FIG. 6. Accordingly, at the terminal end of the slide advance the formed and clamped lash 22a will be spaced from the arcuate forming face 54 of the forming member in order to permit said lash to shrink in a tensionless condition.

The unit 30 will now be indexed at a heating station H, shown schematically in FIG. 1, in which a source of hot air will be applied to lashes 22a. At this station there is provided a reciprocating heat shield 11 which is reciprocated to a projecting position over a frontal surface of the eye shell prior to the application of hot air to the lashes to protect the shell from such hot air. Subsequent to the application of hot air the heat shield 11 will be retracted to its home position. Any suitable source of heat may be used, such as hot air, which applies heat to said lashes to heat the same somewhat below the melting point of the nylon material, which in the instant example is 482° F. It will be understood that the hot air will be discharged through an orifice or nozzle N so as to direct such heated air to the region of lashes 22a. At the heating station H the lashes will shrink in length, as indicated by broken lines 22b in FIG. 6, the shrinking taking place between the clamping point of the lashes and the region of securement thereof to the eye member. The shrinking of the formed strands or filaments imparts the desired curvature thereto, and the unit 30 is sequentially indexed to the next station C, which subjects the shrunk lashes 22b to a cooling source. If desired, the lashes may be arranged to shrink in length to a position over the forming face 54, in which case the shrunk lashes will be set to a curvature conforming to the curvature of said forming face.

Any desired cooling source may be utilized, such as a source of cold air which is discharged through a suitable orifice or nozzle N' to the region of heated lashes 22b so as to set the same at the desired curvature. The doll's eye 10" (FIG. 2a) is shown with lashes 22b subsequent to the curling operation and prior to trimming, lashes 22b being transformed into finished lashes 22' (FIG. 2b) by a trimming operation. If desired, the dial plate may include a trimming station in which the now set curled lashes 22b are trimmed to the desired length and shape, or the trimming may be accomplished off the dial machine in a separate operation.

The dial table will then be sequentially indexed to ejection station E, where any suitable ejection means may be used to strip the doll's eye from its post, it being understood that at the stripping station the slide will be fully

retracted to the position shown in FIGS. 2 and 3 in which the clamping ring 132 is swung clear of the post. The clamping ring 132 is pivoted away from the clamping ring 134 on the return reciprocation of the slide to retracted position, and on this return movement follower 148 contacts with the upper series of cam edges or surfaces of cam slot 162. Subsequent to the stripping or ejection operation the unit 30 will be sequentially indexed to a loading station LS where the post 94 will be ready for re-loading and a repeat cycle, as described above.

It will be understood that the lashes are heated somewhat below the melting point of the lash material, the temperature of the hot air of the heating source of the illustrated embodiment being a function of such variables as duration of heat application, spacing of the outlet nozzle from the lashes, ambient temperature and humidity conditions, volume and velocity of heat source, cross section of filaments or thickness of film, degree and character of lash pigmentation, etc. It has been found that the curvature imparted to the lashes is permanent in character and will withstand a test which subjects the lashes to a temperature of 120 degrees F. and 100 percent relative humidity for a period of 72 hours without alteration of the lash curvature. If the lashes are rigidly held or presed in a curved position and subjected to sequential heating and cooling, the resultant lashes have a tendency to uncurl, when subject to mildly elevated temperature and humidity conditions, rendering the product unacceptable for its intended purpose.

It is believed that the construction and operation of the apparatus for lash curling, and the method of lash curling, will be apparent from the foregoing detailed description. It will also be apparent that while we have shown and described our invention in its preferred form, changes may be made in the structure and method disclosed, without departing from the scope of the invention, as sought to be defined in the following claims.

We claim:

1. A method of curling the lashes of a doll's eye comprising an eye member having a lens and a multiplicity of generally parallel projecting strands circularly arranged over said lens and secured to said member, said strands being formed of a plastic material having the capacity to shrink on the application of heat thereto and being thermally settable in a shrunk condition, comprising the steps of bending back the strands over a forming member and clamping the reversely bent strands in position at a clamping point remote from the region of securement of said strands and member to impart a predetermined curl to said strands, relatively separating the thus curled clamped strands and the forming member to dispose the formed lashes in a tensionless condition to permit the same to shrink while in a curled condition on the application of heat thereto, applying heat to said formed strands to shrink the same between said clamping point and said region of securement, and cooling the thus shrunk curled lashes to permanently set the same in said curled condition.

2. A method of curling the lashes of a doll's eye comprising an eye member having a lens and a multiplicity of generally parallel projecting strands arranged over said lens and secured to said member, said strands being formed of a plastic material having the capacity to shrink on the application of heat thereto and being thermally settable in a shrunk condition, comprising the steps of bending back the strands and clamping the reversely bent strands in a position at a clamping point remote from the region of securement of said strands to said eye member to impart a predetermined curl to said strands, disposing the thus curled strands in a tensionless condition to permit the same to shrink while in a curled condition on the application of heat thereto, applying heat to said curled strands to shrink the same between said clamping point and said region of securement, and

cooling the thus shrunk curled strands to permanently set the same in said curled condition.

3. Apparatus for curling the lashes of a doll's eye in which the lashes are formed of a material having the capacity to shrink on the application of heat thereto and be thermally set in a shrunk condition, said apparatus comprising means for holding the doll's eye in position, a forming member disposed in a predetermined relation with respect to said holding means over which the lashes are reversely bent, means related to said forming member for clamping the free end portions of the curled lashes in a tensionless condition free of said forming member to permit the lashes to shrink upon thermal treatment, means to apply heat to the lashes so disposed causing the curled lashes to shrink, and means to cool the resultant shrunk lashes to permanently set the same in a curled condition.

4. Apparatus for curling the lashes of a doll's eye, comprising means for releasably holding the doll's eye in position, a forming member disposed in predetermined relation with respect to said holding means and having a forming face of predetermined curvature over which the lashes are to be formed, means for clamping free end portions of the lashes in position over said forming face to impart a corresponding curvature to the lashes, and means providing for relative separation between said forming member and the clamped lashes formed thereto to dispose the thus clamped lashes in a tensionless condition free of said forming member to permit the same to shrink upon thermal treatment.

5. Apparatus for curling the lashes of a doll's eye, comprising a support, a slide reciprocable on said support carrying a forming member and a device for spacing and fanning out the lashes disposed below said forming member, a post for releasably holding the doll's eye in position and a clamping device conjointly movable therewith mounted on said support and operatively associated with said slide for movement thereby on predetermined advance movement thereof towards said post, said clamping device being movable between open and closed conditions in response to the movement of said slide, said forming member having a forming face of predetermined curvature and said clamping device in the closed condition thereof being in proximity to said forming face, the advancing movement of said slide towards said post spacing and fanning out the lashes and forming the same over said forming face to impart a corresponding curvature thereto with the clamping device closely to thereby clamp the lashes in position over said forming face, the

continued advancing movement of said slide moving said post and clamping device away from said forming member to thereby space the formed clamped lashes from said forming face to permit said lashes to shrink in a tensionless condition on thermal treatment, and means providing for relative movement between said forming member and slide on the closing of said clamping device.

6. Apparatus for curling the lashes of a doll's eye, comprising a support, a slide reciprocable on said support carrying a forming member and a device for spacing and fanning out the lashes disposed below said forming member, a post for releasably holding the doll's eye in position and a clamping device conjointly movable therewith mounted on said support and operatively associated with said slide for movement thereby on predetermined advance movement thereof towards said post, said device comprising a series of spaced needles arranged in a generally conical relation with the ends of said needles facing said post, said clamping device being arranged to open and close in response to the movement of said slide, said forming member having a forming face of predetermined curvature and said clamping device in the closed condition thereof being in proximity to said forming face, the movement of said slide towards said post projecting said needles through the lashes for spacing and fanning out the lashes and forming the same over said forming face to impart a corresponding curvature thereto with the clamping device closing to thereby clamp the lashes in position, the continued movement of said slide moving said post and clamping device as an assembly away from said forming member to thereby move the formed clamped lashes away from said forming face to permit said lashes to shrink in a tensionless condition, and means providing for relative movement between said forming member and slide subsequent to the closing of said clamping device.
